ELECTRICAL SWITCH

Tomlinson F. Johnson, Atlanta, Ga.

Application March 1, 1940, Serial No. 321,759

3 Claims. (Cl. 200—48)

This invention relates to high tension electrical switches of the type usually employed in sub-stations on high tension systems and, among other objects, aims to provide a greatly improved switch associated directly with a bushing on electrical apparatus such as a transformer or oil circuit breaker. The idea is to utilize a high tension bushing of the existing equipment in lieu of a separate insulator or insulators and to dispense with some of the supporting members of the usual switch assembly, thereby effecting great economy in such switch installations. Another aim is to provide a switch of this type having provision for adjusting the relative positions of the switch jaw and blade to compensate for differences in the height or length of bushings.

Other aims and advantages of the invention will appear in the specification, when considered in connection with the accompanying drawings, 20 wherein:

Fig. 1 is a side elevation of a switch assembly embodying the invention;

Fig. 2 is a fragmentary side elevation on an enlarged scale, showing a pantograph jaw support;

Fig. 3 is a fragmentary view similar to Fig. 2, but showing the pantograph adjusted to another position;

Fig. 4 is a rear elevation of a three phase switch unit of the type shown in Fig. 1; and

Fig. 5 is a vertical end elevation of the jaw support shown in Figs. 1, 2 and 3.

Referring particularly to the drawings, the type of switch there shown is designed to be used in conjunction with a bushing or series of bushings on electrical apparatus such as high tension transformers in substations. However, it is to be understood that such switches may be employed in conjunction with any kind of bushings, such as wall bushings or the bushings of oil circuit breakers. In sub-station equipment the switches for high tension lines leading to transformers and oil circuit breakers are necessarily very large and heavy. They require expensive insulators and when they are separately mounted, must be supported on special beams or supporting frame members. The cost of a single insulator, or groups of insulators, for such switches is quite large. This invention dispenses with one of the insulators usually employed in each of such switches and to utilize the bushing of the electrical apparatus in its stead.

Referring to Fig. 1, the switch is there shown as being mounted to co-act with a bushing 10 of

5 a transformer or oil circuit breaker 11 and in this example the bushing has an adjustable spring jaw 12 which may be of any conventional type or generally like that shown in my Patent 1,914,777. Herein, the jaw is carried by pairs of pivoted links 13 and 14 which, in turn, are pivotally connected to a socket member 15 adapted to be clamped on the upper end of a capacity rod or terminal 16 extending through the bushing 10 by means of a clamping bolt 17, the lower end of the socket 15 being split for that purpose.

10 The arrangement is such that the links 13 and 14 constitute a pantograph for adjusting the switch jaw both vertically and horizontally in the vertical plane of the switch blade. The link pivots are shown as being in the form of bolts 18 so that when the jaw is properly adjusted, the bolts may be tightened to sustain it in its adjusted position. The purpose of the adjustment is to support the jaw properly on bushings of various lengths or to compensate for any difference in the height of the opposite ends of a switch blade when supported on a sub-station structure.

15 In this instance, an articulated switch blade 19 of a well known type cooperates with the switch jaw. As shown in dotted lines in Fig. 1, it has a knee-joint near the middle which breaks slightly upon opening movement and straightens upon closing movement. It is shown as being mounted on a rocking insulator 20 which is pivotally supported by a split saddle 21 on bearing members 22 carried by beams 23 on the sub-station frame structure 24. It will be understood, however, that the frame 24 may be specially designed to carry a gang of such switches and it is so shown in Fig. 4 for carrying the switches of a three-phase circuit. The rocking insulator 20 is limited in its swinging movement by lateral wings 25 on the saddle 21 and adjustable stop pins or members 26 mounted on the supporting beams 23. The insulator 20 is adapted to be rocked by the usual hand crank 27 connected through well known worm and wheel gearing (not shown) in a gear housing 28 to a crank arm 29, operating link 30 and arm 31. The arrangement is such that the switch blade may be swung through approximately 60° to the dotted line position shown in Fig. 1. When the switch is closed, the tip of the articulate blade closes by both swinging and horizontal movement to produce a very powerful spring grip contact with the jaw. Incidentally, the tip portion of the blade 19 is shown as being connected by

a flexible conductor 32 to a high tension line terminal 33 pivoted on the cap of the rocking insulator 20 so that the opening and closing movement of the switch will not bend the lead-in conductor 34.

To relieve the pantograph supported jaws 12 of undue racking strain and to counterbalance the weight of the respective rocking insulators and their switch blades in both the closed and open position, each insulator is shown in Figs. 1 and 4 as having a pair of counterbalancing coil springs 35 mounted on the tension rods 36 connected to arms 37 on the insulator shafts. The rods 36 are slidable through pivoted sleeves 38 having trunnions journaled in brackets 39 supported on the beams 23. The upper ends of the coil springs act against these sleeves and their lower ends against nuts or abutments 40 screwed on the lower ends of the rods. In Fig. 4 the three rocking insulators are shown for convenience as being rocked to their vertical positions or half way between their open and closed positions. They are shown as being connected to operate together by means of shaft sections 41 of the proper length rigidly connected to the respective rocking insulator shafts and the handle 27 is connected to only one of the shaft sections 41, as is usual in gang switch operation.

From the foregoing description, it will be seen that the switch assembly is very simple in its construction and operation. The cost of installation is greatly reduced. The pantograph mounting for the jaw not only permits the necessary adjustments of the jaw, but prevents breaking strains or shocks from being transmitted to the supporting bushings.

Obviously, the present invention is not restricted to the particular embodiment thereof herein shown and described. Moreover, it is not indispensable that all the features of the inven-

tion be used conjointly, since they may be employed advantageously in various combinations and sub-combinations.

What is claimed is:

5. An adjustable contact for high tension electrical switches comprising, in combination, a support; jointed members pivotally and adjustably connected to the support; a switch jaw carried by the jointed members; and means holding the 10 jointed members frictionally adjusted, whereby the jaw may be adjusted in any direction within the plane of movement of a switch blade.

15. In combination with a high tension, air-break electrical switch of the character described having an articulated swinging blade cooperating with a contact supported on a bushing, a cap member mounted on the bushing; a pair of opposed links pivotally and adjustably mounted on the cap member; and a second pair of links pivotally and adjustably connected to the ends 20 of the first pair of links and also pivotally connected to the contact, whereby the contact member may be adjusted pantograph-fashion both vertically and horizontally in the plane of swinging movement of the switch blade.

25. In combination with a high tension, air-break, electrical switch of the character described having a counterbalanced, articulated, swinging blade mounted for endwise movement upon closing and cooperating with a contact support on a transformer bushing, a contact supporting member mounted on the bushing; pantograph links pivotally and adjustably mounted on the contact supporting member and adjustably connected to the contact; and clamping bolts frictionally holding the pantograph links in adjusted positions whereby the contact may be adjusted in all directions in the plane of the swinging movement of the blade.

30. TOMLINSON F. JOHNSON.
